UNITED STATES PATENT OFFICE.

ARTHUR JUNGHANS, OF SCHRAMBERG, GERMANY.

ILLUMINATING-INDICATOR.

1,036,256.

Specification of Letters Patent. Patented Aug. 20, 1912.

Application filed April 13, 1910. Serial No. 555,297.

To all whom it may concern:

Be it known that I, ARTHUR JUNGHANS, 5
privy commercial councillor, a subject of the
King of Wurttemberg, residing at Schram-
berg, in the Kingdom of Wurttemberg, Ger-
many, have invented certain new and useful
Illuminating-Indicators, of which the fol-
lowing is a full, clear, and exact description.

The present invention has for its object
10 a method for fixing the illuminating medium
employed for the indicating parts such as
dials and hands of clocks, scales or the like
in the form of dots, etc., whereby the said
medium is prevented from injury and from
15 falling off.

Heretofore the illuminating medium has
been arranged upon the indicating parts, for
example on an enameled dial, generally in
20 the form of points or dots for example by
boring the dial above the figures to a certain
depth, then coating the bottom of the bore
with adhesive material upon which the
25 illuminating medium was placed, a thin
sheet of celluloid was then stuck upon the
dial over this illuminating material in order
to prevent it from falling out as a result of
shocks. A similar procedure was adopted
30 in applying such illuminating medium to the
hands or the like. This method presents the
defect that the consumption of illuminating
material was very irregular, while in addition
35 this material and the covering mutually
influenced and colored each other, thereby
weakening the luminosity and finally the
protecting coverings, on the dial, particu-
larly impaired the appearance necessarily
40 resulting in rendering the sale of such clocks
more difficult. These defects are obviated
by means of the present method which con-
sists in the first place in providing the indi-
cating parts to which the illuminating mass
45 is to be applied with a through bore or per-
foration, then arranging a covering of glass,
enamel or the like over one side of this part
and finally introducing into the bore thus
50 covered on one side an adhesive material and
then sprinkling the illuminating material
thereon.

By way of example a dial embodying the
invention is illustrated in the accompanying
drawing in which:

Figure 1 shows the dial in elevation and
Fig. 2 is a cross section on line 2-2 of Fig.
1, looking in the direction of the arrows, one

of the perforations being presented without 55
the illuminating mass but with the covering,
and the other with both the illuminating
mass and cover. Fig. 3 is an enlarged sec-
tional view of the left hand portion of
Fig. 2. Fig. 4 is an enlarged sectional view 60
of the right hand portion of Fig. 2.

In accordance with the invention the dial
comprising the metal back or foundation, *a*,
and the enamel covering *a'*, which are both
provided with perforations *b* extending 65
throughout its entire thickness, thereupon
the dial is provided in the furnace with a
covering of glass, enamel or the like so that
a transparent mass *c* is provided above the
perforations which forms windows *c'*, and 70
these perforations are therefore closed in
front. Instead of providing this covering, the
perforations *b* might be closed by fusing in
circular glass disks. The windows *c'* are then
either coated with adhesive material from 75
behind and the illuminating mass *d* arranged
thereon, or elements such as pieces of paper
or cardboard are coated with adhesive ma-
terial, the illuminating mass sprinkled there-
on, whereupon small disks or the like are 80
stamped out in correspondence with the per-
forations or other recesses, these disks being
inserted in the perforations from behind
with the illuminating material against the
window. In the case of other indicating 85
parts such as hands or the like a similar
method is adopted for fixing and securing
the illuminating material. In order to fa-
cilitate the operation the indicating parts
such as the clock hands are made of copper. 90
The bores and cavities on the indicating
parts can be given any desired form and size,
and they can be arranged in any convenient
manner.

What I claim as my invention and desire 95
to secure by Letters Patent is:

1. A self-illuminating device comprising
in combination, a foundation body provided
with a plurality of openings extending
therethrough, a transparent mass fused on 100
one side of said body and extending across
said openings to close the same on one side
of said body, and elements having an illu-
minating material adhered thereto and in-
serted into the openings behind the trans-
parent mass.

2. A self illuminating clock dial compris-
ing in combination, a back portion having

an enamel like covering and openings or
perforations extending through the back
portion and covering, transparent mass ex-
tending across said openings, and self illu-
5 minating material disposed in said openings
from behind said back portion.

In testimony whereof I affix my signature
in presence of two witnesses.

ARTHUR JUNGHANS.
